REINFORCED CLIP AND LINGUAL OR
PALATAL BARS FOR DENTURES

Augustus R. Mackey, Newark, N. J.

Application June 20, 1950, Serial No. 169,150

3 Claims. (Cl. 32—7)

1

This invention relates to improvements in dentures, and more particularly to partial dentures which are clipped to natural teeth so as to be anchored thereby in the mouth of the wearer.

In partial dentures, wherein the opposite plate sections thereof are formed from molded plastic material, the plate sections are provided at their inner ends with suitably shaped clips which are adapted to clasp the natural teeth adjacent to which said inner ends of the plate sections terminate. These clips are provided with shanks adapted to be imbedded in the material of the plate sections. The plate sections are connected one with the other by bars which extend therebetween to lie behind the natural teeth with which the partial denture is associated, when said denture is worn. If the partial denture is designed for application to the lower jaw, the connecting bar is referred to as a lingual bar, but in a partial denture for application to the upper jaw, the connecting bar is referred to as a palatal bar. With respect to both types of connecting bars, the same are secured to the plate sections of the denture by imbedding the end portions thereof in the material of said plate sections.

In partial dentures characterized as above stated, there is considerable risk of either the clasp or the connecting bars breaking away from the plate sections to which they are secured. Having this in view, it is an object of this invention to provide a novel means for reenforcing the connections of the clips and connecting bar with the plate sections of a partial denture, whereby to substantially eliminate risk of breakage, and at the same time greatly strengthen the denture as a whole.

An illustrative embodiment of this invention is shown in the accompanying drawings, in which:

Fig. 1 is a top plan view of a partial denture wherein a novel reinforcing means according to this invention is combined with the clips and connecting bar and the plate sections thereof; Fig. 2 is a transverse vertical section, taken on line 2—2 in Fig. 1; Fig. 3 is a cross-sectional view, taken on line 3—3 in Fig. 1; and Fig. 4 is a fragmentary cross-sectional view, taken on line 4—4 in Fig. 2, but drawn on an enlarged scale.

Fig. 5 is a fragmentary perspective view of the reenforcing element as applied to a clip and an end of a connecting bar adjacent thereto, this view being somewhat enlarged and showing the clip element by broken lines.

Similar characters of reference are employed in the above described views, to indicate corresponding parts.

2

Referring to the drawings, the reference character 10 indicates the plate sections of a partial denture for application to the lower jaw of a wearer thereof. These plate sections are molded from suitable plastic material, and are conformably shaped to fit over the ridge of the wearer's jaw. Mounted in the plate sections are the artificial teeth desired to be supplied by the restoration which the partial denture provides. To the inner end of each plate section 10 is affixed a clip 11 adapted to clasp an adjacent natural tooth in the manner and for the purpose well known to the art. Each such clip 11 is provided with a shank 12 about which the material of the plate section is molded, so as to imbed and anchor said shank therein. Extending between the plate sections 10 is a suitably shaped connecting or lingual bar 13. The material of the plate sections 10 is molded about end portions 14 of the connecting or lingual bar 13, so as to imbed and anchor the ends of the latter to said plate sections.

The clips 11 and the connecting or lingual bar 13 of the denture are made of metallic material which may optionally be of either precious or non-precious metal.

According to the instant invention, a reenforcing means of novel construction and arrangement is combined with each plate section 10 and with its associated clip 11 and anchoring end portion of the connecting or lingual bar 13. In an illustrative embodiment thereof, said reenforcing means comprises a sheet metal formation produced by folding a sheet metal strip across its length into a hollow body 15 of angular or substantially U-shaped cross-section. The body 15 thus produced is then bent to provide an upper arm 16 for extension upwardly between the connecting or lingual bar 13 and the adjacent clip 11, and a lower and rearwardly extending arm 17, angular to said upper arm; for extension from the connecting or lingual bar 13 and shaped to substantially conform to the contour of the inner or rearward marginal bottom edge of the plate section 10. Intermediate the arms 16 and 17, the walls of the body 15 are flattened to engage in mutual meeting relation and are then bowed outwardly so as to extend across and in embracing relation to the connecting or lingual bar 13, thus forming what may be termed a yoke 18 for coupling the reenforcing means to said connecting or lingual bar. The upper end of the upper arm 16 is disposed to abut a portion of the clip 11, and is rigidly secured thereto by means of a soldered joint or connection. The yoke 18 is likewise rigidly secured in its embracing rela-

tion to the connecting or lingual bar 13 by means of a soldered joint or connection. To the assembly thus produced, the material of the plate section 10 is molded, so that the shank 12 of the clip 11 and the end portion 14 of the connecting or lingual bar 13 will be imbedded in the mass of the plate section, and so that the material of the plate section will fill the troughs formed by the interior of the arms 16 and 17 of the reenforcing body 15, whereby the exterior surfaces of said arms are exposed substantially flush with the adjacent external surface areas of the plate section.

The novel reenforcing means, being molded into the plate section and so related to the connecting or lingual bar and to the clip as to be unitary therewith, strongly reenforces the anchorage of both the connecting or lingual bar and the clip to the mass of the plate section. By reason of this, working of the imbedded end portion 14 of the connecting or lingual bar and of the shank 12 of the clip relative to the mass of the plate section 10 is strongly resisted, and consequently tendency of these parts to loosen relative to the latter is prevented. Furthermore, owing to the bracing support by the reenforcing means of portions of the connecting or lingual bar and of the clip at the points of emergence thereof from the plate section mass, application of bending stresses or strains to said portion is prevented, so that risk of weakening, crystallization and ultimate breaking of said portions is likewise avoided. It will thus be apparent that not only is the union of the connecting or lingual bar and of the clip with the plate section strongly reenforced against breakage, loosening or detrimental deformation, but also the entire structure of the partial denture is greatly strengthened, so that its desired fit relative to the jaw ridge and natural teeth of the wearer is stabilized, and firmness, security and wearing comfort of the denture is therefore assured.

While the combination of the novel reenforcing means with the plate sections, lingual bar and clips of a partial denture for application to a lower jaw has been specifically shown and described, it will be understood that the novel reenforcing means may be similarly combined with the plate sections, palatal bar and clips of a partial denture application to an upper jaw with equal advantage.

Having now described my invention, I claim:

1. In a partial denture comprising spaced plate sections joined by a connecting bar the end portions of which are imbedded and anchored in the respective plate sections and said plate sections having clips projecting from their inner ends the shanks of which are likewise imbedded and anchored therein, the combination with the foregoing elements of an external reenforcing

body affixed to and embracing an edge portion of each plate section, and said body having an upwardly directed end portion extending across and affixed to the connecting bar and extending therefrom to the adjacent clip with its extremity affixed to said clip.

2. In a partial denture comprising spaced plate sections joined by a connecting bar the end portions of which are imbedded and anchored in the respective plate sections and said plate sections having clips projecting from their inner ends the shanks of which are likewise imbedded and anchored therein, the combination with the foregoing elements of a sheet metal reenforcing body for attachment to each plate section, each body being folded longitudinally to provide a hollow interior of inwardly open substantially U-shaped cross-section within which the material of a plate section is molded whereby to affix the body to and for external extension along and in embracing relation to a free edge portion of said plate section at the inner end part thereof, said body having a bowed yoke portion intermediate its ends disposed to extend across and embrace the connecting bar in affixed relation to the latter, and said body extending from the connecting bar to the adjacent clip with its extremity affixed to said clip.
3. In combination with a plate section of a partial denture, a clip extending from the inner end of said plate section and having a shank imbedded in the material of said plate section, a connecting bar having an end portion imbedded in the material of said plate section and an external portion extending from the inner end of said plate section in downwardly spaced relation to said clip, a sheet metal reenforcing body folded longitudinally to provide a hollow interior of inwardly open substantially U-shaped cross-section by which the lower rearward edge portion and an end edge portion of the plate section is embraced and affixed, the walls of said body at a point adjacent its upper end being flattened together and outwardly bowed to provide a yoke portion disposed to extend across and to embrace the connecting bar in affixed relation thereto, and the upper end portion of said body extending from said connecting bar to said clip with its extremity affixed to the latter.

AUGUSTUS R. MACKEY.
